WIRE BASKET AND DIVIDER FOR THE
SAMEErnest H. Schilling, Lafayette, Ind., assignor to
Peerless Wire Goods Company, Inc., Lafayette,
Ind., a corporation of Indiana

Application May 26, 1934, Serial No. 727,633

2 Claims. (Cl. 220—19)

The object of my invention is to provide a ventilated tray-like partitioned basket particularly useful as a container, within a refrigerator, of various articles varying from time to time in quantity, the structure being of such character as to be readily and cheaply manufactured and yet substantial and sanitary.

The accompanying drawing illustrates my invention:

10 Fig. 1 is an end elevation;

Fig. 2, a plan with a medial strip of the structure omitted;

Fig. 3, a fragmentary vertical section of a plane parallel with one of the adjustable partitions;

15 Fig. 4, a side elevation of one end of one of the adjustable partitions, on a larger scale;

Fig. 5, an end elevation of the structure shown in Fig. 4;

20 Fig. 6, a fragmentary vertical section of one arm of one of the main frames and an adjacent partition of one of the vertical bars; and

Fig. 7, a detail similar to Fig. 4 but of a modified form of partition guiding means.

In the drawing 10 and 11 indicate rectangular frames of wire connected by wire verticals 12 soldered or welded at their upper and lower ends to the inner sides of the frames 10 and 11 as indicated in Fig. 6. Lateral, bottom-forming wires 14 are similarly attached to the lower frame 11 to form a ventilated bottom for the basket or tray. At each end of the structure are the vertical legs 15 of a U-shaped supporting-leg structure secured to the inner faces of the frames 10 and 11 at or about the corners thereof. The lateral or intermediate bar 16 of this U-shaped structure is displaced outwardly from the vertical plane of the arms 15, as shown in Fig. 1, the construction being such as to afford supporting feet which will hold the frame 11 somewhat above the supporting surface.

Adjustable partitions are formed by rectangular frames 20 (Fig. 4) of wire, opposite sides of which are connected, at intermediate points by wires 21. Each vertical end wire 20' of frame 20 is provided with a U-shaped guideway adapted to receive and slide upon one of the verticals 12. In Fig. 5 and at the left of Figs. 1 and 2 and in Fig. 4 this guide structure is shown as formed of a continu-

ous loop of wire having medial parallel portions 22, 22 and U-shaped footings 23, 23 which are laterally displaced from the plane of the parts 22, 22 and are welded or soldered to wire 20' so that the parts 22, 22 may straddle any one of 5 the verticals 12.

It will be readily understood that various modifications of this guide structure may be provided without departing from the spirit of my invention. For instance, at the right of Figs. 1 and 2, 10 and in Fig. 7, I provide a sheet metal guide structure comprising a plate 25 having lateral ears 26, 26 bent up at right angles to plate 25 and spaced apart a distance slightly greater than the diameter of a vertical 12 with the main body of the plate 15 secured to a rod 20'.

The partitions may be readily withdrawn vertically and replaced in association with any desired pair of verticals 12, 12, thus providing compartments of any desired size, within the tray-like 20 structure, for the reception of desired articles.

I claim as my invention:

1. A basket-like structure comprising upper and lower wire frames, connecting wire verticals attached to the inner faces of said frames and projecting inwardly from said frames, and a separable partition comprising a main frame having, at each end, a vertically extended guide structure comprising two laterally spaced vertically extending substantially parallel portions spaced 30 apart to receive any one of said frame verticals, the overall length of the partition and associated guide structures being less than an internal transverse dimension of the upper frame.

2. A basket-like structure comprising upper and lower wire frames, a plurality of wire verticals extending between and secured to the inner sides of said frames, a separable partition comprising a main wire frame having vertical ends, and a guide structure secured to each of said partition 40 verticals, said guide structure formed from a single wire in two parallel medial portions and two U-shaped end portions laterally displaced from the plane of the intermediate portions and secured to the partition vertical, the intermediate 45 portions being spaced apart to slidably straddle a frame vertical.

ERNEST H. SCHILLING.
